UNITED STATES PATENT OFFICE.

JOHN HENRY GATELY, OF BELLows FALLS, VERMONT, ASSIGNOR OF
ONE-HALF TO JOHN P. RILEY, OF BELLows FALLS, VERMONT.

WINDING-CORE.

No. 839,378.

Specification of Letters Patent.

Patented Dec. 25, 1906.

Application filed October 23, 1905. Serial No. 284,087.

To all whom it may concern:

Be it known that I, JOHN HENRY GATELY, a citizen of the United States, residing at Bellows Falls, in the county of Windham and State of Vermont, have invented a new and useful Winding-Core, of which the following is a specification.

This invention relates to winding-cores for the support of roll goods, particularly for use in connection with paper-making machines to have the paper wound thereon as it comes from the machine. Cores of this character are usually formed of paper and tubular in form so as to receive a drive element in one or both ends thereof, one and in some instances each end of the core being provided with a notch or seat to receive a pin or key carried by the drive element for retaining the core therewith. The rubbing of the pin or key upon the walls of the notch soon wears the same, which impairs the connection between the drive element and the core. Furthermore, the torsional strain upon the core tends to crack the same, wherefore the life of such cores is comparatively short.

Having appreciated the foregoing objections, I propose to obviate the same in a simple and novel manner by a peculiar reinforcing of each end of the core, so as to brace the same against torsional strain and also to take the wear of the pin or key carried by the drive element, thereby to maintain the most effective connection between the drive element and the core and to materially prolong the life of the core.

With these and other objects in view the present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the accompanying drawings, Figure 1 is a fragmentary sectional view of a tubular core having the reinforcement of the present invention applied thereto, a conventional form of drive element being shown in dotted lines. Fig. 2 is a detail perspective view

looking at the inner end of the reinforcing element. Fig. 3 is a similar view looking at the outer end thereof.

Like characters of reference designate corresponding parts in each and every figure of the drawings.

In Fig. 1 of the drawings there has been shown a fragmentary end portion 1 of a conventional winding-core as employed in connection with paper-making machines for receiving and storing the paper as it is produced by the machine. Such cores are tubular and open-ended, and while they may be formed of any material they are usually made of paper, so as to be comparatively light and at the same time possess sufficient strength and durability. A core is ordinarily driven from a cylindrical drive element, such as indicated in dotted lines and designated 2, the reduced extremity 3 of which is introduced into the adjacent open end of the core and provided with a radial projection or key 4, adapted to take into a notch in the end of the core, so as to interlock these elements for simultaneous rotation. It is obvious that the projection or key 4 wears the walls of the notch and the torsional strain tends to crack the core. These objections are overcome by the employment of the present reinforcement, which consists of concentric spaced inner and outer sleeve members 5 and 6, which are terminally connected by an integral annular ring or web 7. The end of the core is received between the sleeve members 5 and 6 and is provided with the external and internal annular rabbets 8 and 9 for the reception of said sleeve members, whereby the latter are flush with the adjacent faces of the core. The outer sleeve member is provided with an annular series of perforations 10 for the reception of threaded fastenings or rivets 11, which pierce the core, and thereby rigidly maintain the reinforcement element 95 upon the core. A notch 12 is formed in the ring or web 7 for the reception of the projection or key 4 of the drive element 2, whereby the latter bears against a metallic surface instead of against the material of the core, which prevents wearing of the core by the pin or key. Moreover, as the end of the core is snugly embraced between the sleeve members of the reinforcement element it is stiff-

ened and strengthened, and the reinforcing element takes the torsional strain, and thereby prevents splitting and cracking of the core.

5 The inner annular edge of the web 7 is beveled, as shown at 13, so as to bear against the annular beveled portion 14 of the drive element, whereby a wedging action is had between the drive element and the reinforcing element, which constitutes a connection between these elements in addition to the connection afforded by the pin or key 4, fitting in the seat or notch 12.

10 An important feature of the present device resides in the fact that the seat 12 intersects the outer periphery of the device, whereby the device will accommodate the key 4 even though the latter may be longer than the width of the seat.

15 From the foregoing description it will be understood that the reinforcing element of the present invention may be applied to any ordinary tubular core without making any material change therein beyond producing

20 the inner and outer rabbets for the reception of the sleeve members of the reinforcing element. Moreover, the reinforcing element is arranged to properly receive the interlocking pin or key carried by the drive element, and 25 therefore no change in the drive connection is necessary.

Having thus described the invention, what is claimed is—

1. A tubular winding-core having annular recesses in the inner and outer faces thereof 35 at one end, the inner recess extending farther into the core than the outer recess and the end of said core being smooth and uninterrupted, a sleeve fitted within the outer recess, means extending therethrough and into the 40 core for fastening the sleeve upon the core, a sleeve within the inner recess and extending beyond the inner edge of the outer sleeve, a web connecting the sleeves and bearing upon the end of the core, said web having a key- 45 receiving seat extending thereinto.

2. A reinforcing attachment for winding-cores comprising inner and outer concentric sleeves having a connecting-web at one end, said inner sleeve being longer than and projecting beyond one end of the outer sleeve, and said web having a key-receiving seat extending into the outer face thereof and intersecting the inner and outer peripheries of the reinforcing attachment.

50 In testimony that I claim the foregoing as my own I have hereto affixed my signature in the presence of two witnesses.

JOHN HENRY GATELY.
